UNITED STATES PATENT OFFICE.

WARREN B. REED AND WALTER HEPLER, OF MORGAN CITY, LOUISIANA.

DRILLING APPARATUS.

1,378,056.

Specification of Letters Patent. Patented May 17, 1921.

Application filed June 21, 1920. Serial No. 390,494.

To all whom it may concern:

Be it known that we, WARREN B. REED and WALTER HEPLER, both citizens of the United States, residing at Morgan City, 5 in the parish of St. Mary and State of Louisiana, have invented certain new and useful Improvements in Drilling Apparatus; and we do hereby declare the following to be a full, clear, and exact description of the invention, such as will enable others skilled in the art to which it appertains to make and use the same.

This invention relates to well drilling apparatus and has for its object to provide 15 apparatus of this character which will be simple in construction, comparatively inexpensive to manufacture, assemble and maintain, and more efficient in operation than those heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views:—

Figure 1 is a diagrammatic vertical sectional view of an apparatus made in accordance with this invention;

Fig. 2 is an enlarged fragmentary sectional view of the lower portion of the parts shown in Fig. 1; and

Fig. 3 is a cross sectional view taken on the line 3—3 of Fig. 2, looking down.

In the drilling of oil and other wells it is often desirable to obtain samples or "returns" of the various strata, through which 40 the drill passes and in many instances it is also desirable to know the kind of formation lying just ahead of the hole which is being bored to size, in which cases a core such as would be produced with a diamond drill in formations that would permit of its use, would be of extreme value to the driller.

In the rotary system of drilling wells the samples of the cuttings of the "fish-tail" or other type of bit are brought to the surface 50 by means of water which is pumped down through the hollow drill stem, through the bit at the bottom of the hole, and then back up outside the drill stem. These cuttings are brought up solely by the flowing water, 55 in a very diluted form and often stick to the sides of the well, resulting in a very

incomplete data regarding the strata or formations through which the well is being drilled. This is a serious disadvantage in drilling by the rotary system, since it frequently results in the entire overlooking of many valuable strata through which the 60 drill has passed, and it is one of the objects of this invention to provide means whereby samples of the unwashed cuttings may be 65 readily obtained for examination.

Referring to the drawings, 1 indicates a lower section of the drill stem, which stem is preferably in the form of a hollow pipe reaching to the top of the well and constituting a conduit through which the wash water is pumped down to bring up the cuttings in the usual manner. Connected to the said stem 1 as by the screw-threaded coupling 2 is a nipple member 3 having a bore 4, and having its lower portion enlarged or flared as at 5 and provided with an enlarged bore 6, all as will be clear from Fig. 1.

Screw-threaded within the bore 4 and extending down into the bore 6 is a plug 7 80 provided with a bore or channel 8 communicating with the said bore 4, and having a plurality of branches 9 leading to the bore 6. The plug 7 is also provided with a second bore 10 and is connected at its lower end as 85 by the coupling 11 to the pipe 12, which constitutes a chamber to receive the dry cuttings, as will more fully appear below.

The lower end of the pipe 12 is threaded into the shank of the rotary shoe or cutter 90 member 13, which is provided with the bore 14 into which is threaded or otherwise secured the "fish-tail" or other bit 15, see Figs. 1 and 2. The shank 16 of the said bit 15 is bored as at 17, providing a pair of openings 95 18 communicating with either side of the blade of the bit 15, through which the cuttings from the said bit may pass, as will be readily apparent.

Within the bore or chamber 14 of the rotary shoe 13 is a suitable check valve, here shown as a pair of hinged semi-circular leaves 20, mounted upon the hinge pin or rod 21 carried by the said shoe 13, and adapted when in their closed position, shown 105 in Fig. 1, to fit the circumference of the bore 14 and to seat upon the surface 22 of the bit shank 16. It will thus be apparent that the said leaves 20 may swing upwardly, as shown in Fig. 2, to permit the passage of 110 any cuttings which may be forced up from the passage 17, but that they will swing

downwardly and seat upon the surface 22 to prevent the return of such material as has passed them, acting in this respect as a flap valve.

5 Secured to the lower portion 5 of the nipple 3 as by the coupling 25 is the pipe or casing 26 surrounding the pipe 12 and providing an annular passage 27 for the downwardly flowing water, and secured to the 10 bottom of the said casing 26 is the rotary cutter or shoe 28, employed to ream the hole to size in the usual manner. The said casing 26 is of course smaller in diameter than the reamed hole produced by the cutter 28, 15 whereby an annular space 29 is provided for the return of the wash water with the cuttings from the said cutter.

The bore 10 of the plug 7 is connected to the said annular space 29 by means of a 20 threaded bushing 31, extending through the portion 5 of the nipple 3 and the bore 6 thereof and into the plug 7, and the bore 32 of the said bushing 31 is adapted to be closed by a threaded plug 33, as will be apparent from Fig. 1.

The operation of the device will be clear from the foregoing, but may be briefly summarized as follows:—

In beginning the well, the drilling operations are carried on in the usual manner incidental to the rotary method of drilling. When, however, it is desired to learn the character of the strata or formations ahead of the drilled hole, the drill stem 1 is withdrawn from the hole, the usual bits or other drilling apparatus removed therefrom, and the device here illustrated is attached to the lower end of the said stem, which is then reintroduced into the hole. Upon the rotation of the apparatus, the bit 15 and the shoe 13 will cut into the earth at the bottom of the drilled hole, and the cuttings therefrom will be forced up along the flat sides of the bit 15 and into the openings 18 and bore 17.

45 As the cutters descend additional cuttings will find their way into the bore 17, forcing open the leaves 20 of the check valve, and entering into the pipe 12, as will be readily apparent. When the pipe 12 is filled, the 50 tool may be withdrawn from the hole, and the cuttings contained therein examined. This cutting operation being carried on in the dry, the cuttings contained within the pipe 12 will form layers or strata corresponding exactly to the strata through which the bits have passed, and the driller is thus enabled to ascertain with great certainty the character of the formations through which the reamed hole will pass.

60 The bits 15 and 13 produce a bore 40 of a predetermined diameter and this said bore is reamed to any desired size by the rotary shoe or cutter 28 which follows the cutters 15 and 13 at from say 12 to 36 inches or 65 more. The cuttings from the shoe 28 may

be washed up in the usual manner by water pumped down through the hollow drill stem 1, the passages 4, 8, 9, and 27 to the said shoe, and thence upward in the annular space 29 outside the casing 26 to the top of the well. 70

The apparatus may be used either with or without the threaded plug 33 in place in the bushing 31. When the said plug is in place, as shown in Fig. 1, the chamber within the pipe 12 is substantially air tight, and when the tool is lowered into the hole no liquid enters the said chamber except a small amount due to the compression of the air therein, which amount will vary according to the depth at which the tool is working. 75 In any such case, however, the amount of liquid is negligible and the cuttings are brought to the surface in substantially a dry state.

On the other hand, if desired the plug 33 80 may be removed, in which case the pipe chamber 12 will be filled with water, which will be displaced and forced upward by the incoming cuttings. In this case, the samples brought up will of course be more 85 moistened than when the plug 33 is used, but nevertheless good results may be obtained when operating in this manner.

It is obvious that those skilled in the art may vary the details of construction as well 90 as the arrangement of parts without departing from the spirit of the invention and therefore we do not wish to be limited to the above disclosure except as may be required by the claims. 100

What we claim is:—

1. In an apparatus of the class described the combination of a cutter member; a second cutter member adapted to operate in advance of said first cutter member; means whereby fluid may be supplied to said first cutter member to remove the cuttings therefrom; and means adapted to receive the cuttings produced by said second member, and to maintain them out of contact with said fluid; substantially as described. 105

2. In an apparatus of the class described the combination of a cutter member; a second cutter member adapted to operate in advance of said first cutter member; means whereby fluid may be supplied to said first cutter member to remove the cuttings therefrom; means adapted to receive the cuttings produced by said second member, and to maintain them out of contact with said fluid; and means adapted to control the entrance to said last named means; substantially as described. 115

3. In an apparatus of the class described 120 the combination of a cutter member; means whereby fluid may be supplied to said cutter member to remove the cuttings therefrom; a plurality of additional cutter members adapted to operate in advance of said 125 130

- first cutter member; a chamber associated with said last named cutter members adapted to receive the cuttings therefrom and protect them from said fluid; and a valve 5 associated with said last named cutters adapted to control the entrance to said chamber; substantially as described.
4. In an apparatus of the class described the combination of a cutter member; means 10 associated with said cutter member adapted to receive cuttings therefrom; means adapted to control admission of said cuttings to said receiving means; and means whereby fluid may be admitted or excluded from said 15 receiving means at will; substantially as described.
5. In an apparatus of the class described the combination of a cutter member; a second cutter member adapted to operate in 20 advance of said first member; means whereby fluid may be supplied to said first cutter member to remove the cuttings therefrom; means adapted to receive cuttings from said second cutter member; means adapted to 25 control the admission of said last named cuttings to said receiving means; and means whereby fluid may be admitted or excluded from said receiving means at will; substantially as described.
6. In an apparatus of the class described the combination of a rotatable cutter member; means whereby fluid may be supplied to said cutter member to remove the cuttings therefrom; a second cutter member 30 adapted to operate in advance of said first cutter member; means adapted to prevent 35
- said fluid from reaching said second cutter member, whereby its cuttings are maintained in a substantially dry state; and means adapted to receive said last named 40 cuttings and to maintain them out of contact with said fluid.
7. In an apparatus of the class described the combination of a rotatable cutter member; means adapted to rotate said member, 45 and providing passages whereby fluid may be conducted to and from the latter; a plurality of additional cutter members adapted to operate in advance of said first cutter member; a chamber associated with said last 50 named cutter members, adapted to receive cuttings therefrom; and means communicating with said chamber and one of said fluid passages, whereby fluid may be admitted to or excluded from said chamber at will. 55
8. In an apparatus of the class described the combination of a rotatable cutter member; means for rotating said member and adapted to provide passages whereby fluid may be conducted to and from the latter; a second cutter member rigid with said rotating means and adapted to operate in advance of said first cutter; means adapted to control the entrance to said receiving means; and a connection between said receiving 60 means and one of said fluid passages whereby fluid may be admitted to or excluded from said receiving means at will.
- In testimony whereof we affix our signatures.

WARREN B. REED.
WALTER HEPLER.
